UNITED STATES PATENT OFFICE.

STEPHEN J. COX, OF NEW YORK, N. Y.

WATER-CLOSET MAT OR TOILET-PROTECTOR.

SPECIFICATION forming part of Letters Patent No. 349,784, dated September 28, 1886.

Application filed June 7, 1886. Serial No. 204,408. (No model.)

To all whom it may concern:

Be it known that I, STEPHEN J. COX, a resident of the city, county, and State of New York, have invented a new and useful Water-Closet Mat or Toilet-Protector, of which the following is a specification.

My invention consists of a mat for use in water-closets, adapted for folding, so as to be conveniently carried about, readily opened and spread out upon the seat, for use upon the same to prevent contact of the person with the seat, and also to obviate chilliness, the formation thereof being as hereinafter described, reference being had to the accompanying drawings, in which—

Figure 1 is a plan view of the mat spread out, and Fig. 2 is a section of the same applied to a water-closet seat.

A represents the mat, formed of any suitable material, but more especially and preferably of medicated paper. Vulcanized cloth or flannel with a water-proof backing are also suitable. Centrally is arranged a single row of perforations, *a*, in elliptical form corresponding with the usual hole in the water-closet seat, and this portion of the mat encircled by the perforations may be readily torn away, following the curved line of the perforations, when required for use. When made especially for gentlemen, a portion, *B*, is left as a guard to be bent down into the hole or basin, as shown in Fig. 2, to prevent contact of the genital organs with the seat or bowl beneath. Inside of the elliptical row of perforations a row of perforations is made lengthwise the ellipse, and another crosswise the same, as shown at *b*, Fig. 1. These rows of perforations facilitate the folding of the mat, so that it may be carried about as readily and conveniently as a pocket-handkerchief in the pocket or reticule. They answer as a crease in that respect, and when requisite for use, after the field of the ellipse is removed, admit of the same being parted into four parts for use as toilet-paper for the usual purpose of cleanliness with respect to the rectum, &c.

The mat is square, or it may form a parallelogram; but a circle or elliptical shape for the portion outside the central ellipse would be objectionable, as that would constitute it a ring after the removal of the central field, and a ring of paper especially would not keep its proper position upon the water-closet seat or

remain properly flat or keep to the hole in the seat, even if never folded, but after it has been folded the difficulties attending a circular form are greatly increased, therefore I make it of the shape shown, as the angles and spread consequent upon such shape cause and enable the mat to spread flat upon the seat, also to keep flat without crinkle and to keep its position with respect to the hole in the seat. It is also more conveniently folded and carried when of the shape shown. The central cross of perforations is also essential in folding; and, further, it is necessary to the ready and perfect separation of the removed portion to enable it to be used as toilet-paper, as the nature of the thin medicated paper is such that it will not tear straight, but becomes useless unless perforated for separation, emphatically waste paper and not useful toilet-paper.

It is well known to the medical profession and elsewhere that women are frequently seriously injured, and often suffer great pain, from sitting upon anything cold, which chilling the organs of maternity bring on troublesome complaints, especially during the menstrual period. This mat forms an effectual toilet-protector, conveniently carried about, and always ready for use, constructed of material warm in its nature, preventing direct contact of the person with the closet-seat, obviating all risk of chilliness. It also prevents dissemination of infectious diseases.

What I claim as new, and desire to secure by Letters Patent of the United States, is—

1. A portable water-closet mat rectilinear in shape provided centrally with a single row of perforations in curved line forming an ellipse, the field of which is divided into four parts by a lengthwise and crosswise row of perforations, essentially as shown and described.

2. The water-closet mat *A*, of medicated paper, provided centrally with a single row of perforations, *a*, arranged in curved line forming an ellipse, at one end of said ellipse the said curved line of perforations re-entering the ellipse to form the portion *B*, and the field inclosed within the aforesaid perforations *a* divided into four parts by the cross-lines of perforations *b*, as shown and described.

STEPHEN J. COX.
